UNITED STATES PATENT OFFICE.

YONEZO TSUJINO, OF NEW YORK, N. Y.

AMUSEMENT APPARATUS.

Application filed May 20, 1927. Serial No. 193,004.

This invention relates to improvements in amusement apparatus.

The primary object of the invention resides in an amusement apparatus or game device especially adapted for use in amusement parks or like pleasure resorts, the same being of the roll ball type wherein the skill of the player is essential in the successful operation of the same, and from which a player may derive much pleasure and enjoyment.

Another object of the invention is to provide an amusement apparatus which includes a table of a given length having a rotating target at the foot thereof at which balls are rolled from the opposite end and over the table, but which balls must pass through a restricted passage in their travel to the target, the said target having pockets arranged radially thereon for successive registration with the restricted passage, each pocket being identified by a number, it being the object of the game to deposit the balls in the pockets of the highest number whereby to obtain a relatively high score. From the arrangement, it will be readily appreciated that exceptional skill is required on the part of a player as the ball must be accurately timed to deposit the same in a selected pocket.

Another object is to provide an amusement apparatus of the above kind in which the balls deposited in the pocket are held captive during the rotation of the target and until a player has completed his turn by placing all of the balls therein, whereupon the next player places a coin of a particular denomination into a coin controlled mechanism and he then actuates the same causing the release of the balls and the automatic return of the same to a position at the player's end of the table.

With these and other objects in view, the invention resides in certain novel construction and combination and arrangement of parts, the essential features of which are hereinafter fully described, are particularly pointed out in the appended claims, and are illustrated in the accompanying drawing, in which:

Figure 1 is a perspective view of my improved game apparatus.

Figure 2 is a top plan view of the same.

Figure 3 is a vertical longitudinal sectional view on the line 3-3 of Figure 2.

Figure 4 is a vertical transverse sectional view on the line 4-4 of Figure 2.

Figure 5 is a vertical sectional view on the line 5-5 of Figure 3.

Figure 6 is a detail perspective view of 60 the ball release door actuating device.

Figure 7 is an enlarged detail perspective view of one of the ball pockets.

Referring more particularly to the drawings, the reference numeral 10 designates my 65 improved amusement apparatus in its entirety and which includes broadly, a table 11 having a rotatable target 12 at one end thereof, and a ball release mechanism 13.

The table 11 comprises an enclosed area 14 70 having a recess or trough 15 at the head thereof for receiving the balls 16 which are used in the playing of the game device. The players participating in the game take up a position at the head of the table and roll 75 the balls over the enclosed area in a manner presently to be described. Interposed between the target 12 and the players' end of the table, is a restricted passage 17 which is disposed midway between the sides of the 80 table and of a size to freely permit the balls 16 to roll therethrough. The top of the table from the head to the restricted passage 17 is perfectly level but that portion behind the restricted passage or gate 17 is inclined down- 85 ward as at 18 to cause the ball after passing through the restricted passage to roll down into engagement with the target 12.

The target 12 hereinbefore mentioned comprises a circular disk 19 which is rotatably 90 mounted in a bracket 20 supported by the table and which disk has individual pockets or cages 21 arranged radially therearound and which pockets are provided in their fronts with ball entrance openings 22, the 95 outer sides of the pockets being open as at 23 for permitting the balls to pass therethrough for a purpose to be hereinafter explained. Each pocket is identified by suitable indicia such as numbers 24, which numbers represent the amount of points credited to a player whose ball is deposited therein. For more definitely identifying the pockets, the background of the numbers may be of different colors. The target is so mounted 100 that upon rotation of the same, the respective pockets will successively align with the restricted passage 17 in order that a ball rolled straight through the restricted passage and in timed accord with the move- 105 110

ment of the target will cause the ball to enter the selected pocket or that pocket which is in registration with the restricted passage when the ball reaches the target.

6 For preventing the balls from dropping through the discharge opening 23 in the pockets after the same have been deposited therein, I provide a semi-circular guard 25 which is disposed in spaced relation to the 10 periphery of the target and extends slightly above the horizontal axis of the same. It will be appreciated that after the pockets reach a point above the horizontal axis of the target during rotation of the same, they 15 will roll to the inner bottom of the pockets where they are prevented from escaping by the guard 25.

For the purpose of imparting a slow rotary movement to the target 12, I provide a 20 relatively large pulley wheel 26 on a stub shaft 27 on which the target is mounted while a belt 28 passes over this pulley and over a small pulley 29 fixed to the driven shaft of an electric motor 30. It will be 25 seen that when the motor 30 is turned on, motion will be transmitted from the motor shaft to the pulley 26 thus causing a relatively slow rotation of the target.

The ball release mechanism 13 hereinbefore mentioned comprises a ball release door 31 which is mounted in the guard wall 25 on one side of the vertical axis of rotation of the target and which door normally tends to move to an open position by a suitable 35 spring 32. However, the door is held closed by the action of a spring 33 whose tension is greater than the spring 32 and which spring 33 is arranged in the length of a pull cable 34, one end of said cable being connected to 40 one branch of a bell crank lever 35 while the other branch of the bell crank is connected to a cable 36 which latter cable has connection with the ball release door 31. The other end of the cable 34 is operatively connected to a coin controlled mechanism 35, the construction of which is shown and described in my co-pending application, Sr. No. 192,403, filed May 18th, 1927. This mechanism is operable by the insertion of a 50 coin therein which permits the actuation of the same by causing a pull upon the cable 34 which by reason of the operation of the bell crank 35 causes a slack in the cable 36 thus permitting the spring 32 to automatically 55 move the door 31 to an open position, from where the balls drop into an inclined trough 37 which returns them to the head of the table and allows them to roll through an opening 38 in the side wall of the table and 60 to come to rest in the recess 15 at the head thereof.

In the operation of the device, we shall presume that three balls are used in the playing of the game. The player rolls each 65 ball separate with an effort of causing the

same to pass through the restricted passage 17 and into a selected pocket, it being to his advantage to place the ball in the pocket having the highest value. Therefore, before 70 rolling the ball, he watches the target and times the shot so that the ball 16 enters the selected pocket when in register with the restricted passage 17. Should a ball not pass the restricted passage 17, it is returned to the player and he again rolls the same and 75 continues until all three of the balls have been placed in the pockets of the target, the said pockets being of such a size that only one ball is capable of being received therein. After the balls have been deposited in the 80 pockets, the player is credited with the amount indicated on the pockets having the balls therein and is given a prize for his skill. It will be appreciated that the higher the score the more elaborate the prize. The 85 next player desiring to try his skill, deposits a coin in the coin controlled mechanism 35 and actuates the same causing the opening of the ball release door 31 whereupon the 90 balls are permitted to escape as the respective pockets come into register therewith. The balls return to a position at the head of the table from where the next player may 95 pick them up for use.

While I have described what I deem to be the most desirable embodiment of my invention, it is obvious that many of the details may be varied without in any way departing from the spirit of my invention, and I therefore do not limit myself to the exact details 100 of construction herein set forth nor to anything less than the whole of my invention limited only by the appended claims.

What is claimed as new is:—

1. An amusement apparatus comprising a 105 table, a member rotatably mounted at one end thereof on a horizontal axis, radially arranged pockets provided on said member for movement into and out of alignment with the top of said table, and a restricted passage on said table forward of said member to freely permit a ball rolled over said table to pass therethrough and enter the pockets as the same successively align therewith.

2. An amusement apparatus comprising a 110 table, a member rotatably mounted at one end thereof, radially arranged pockets provided on said member, each pocket having an entrance opening and a discharge opening therein, a restricted passage on said table 115 forward of said member to freely permit a ball rolled over said table to pass therethrough and enter the entrance opening of said pockets as the same successively align therewith, identifying indicia adjacent the respective pockets for distinguishing one from the other, and manually operable means for releasing the balls from said pockets through the discharge openings during 120 rotation of said member after the result de- 125

- terminated by the indicia on the pockets containing the trapped balls has been ascertained.
3. An amusement apparatus comprising a table, a member rotatably mounted at one end thereof, radially arranged pockets provided on said member, a restricted passage on said table forward of said member to freely permit a ball rolled over said table to pass therethrough and enter the pockets as the same successively align therewith, identifying indicia adjacent the respective pockets for distinguishing one from the other, manually operable means for releasing the balls from said pockets during rotation of said member after the result determined by the indicia on the pockets containing the trapped balls has been ascertained, and means for automatically returning the released balls to the opposite end of said table.
4. An amusement apparatus comprising a table, a member journalled for rotation at one end thereof, radially arranged pockets provided on said member, each pocket having an entrance opening and a discharge opening therein, a restricted passage forward of said pockets for the free passage of a ball therethrough and with which the entrance openings of the pockets successively align, means for imparting a continuous rotation to said member, and manually operable means for releasing said balls from the discharge openings of said pockets during rotation of said member.
5. In an amusement apparatus, a rotatable target comprising a disk member and a plurality of pockets arranged radially thereon, each pocket having an entrance opening in the front thereof, and a discharge opening in the outer sides thereof.
6. In an amusement apparatus, a rotatable target comprising a disk member and a plurality of pockets arranged radially thereon, each pocket having an entrance opening in the front thereof and a discharge opening in the outer sides thereof, and a guard wall extending about the target for a distance slightly above the horizontal axis of the same for closing said discharge openings during an interval on each revolution of said target.
7. In an amusement apparatus, a rotatable target comprising a disk member and a plurality of pockets arranged radially thereon, each pocket having an entrance opening in the front thereof and a discharge opening in the outer sides thereof, a guard wall extending about the target for a distance slightly above the horizontal axis of the same for closing said discharge openings during an interval on each revolution of said target, a door in said guard wall normally disposed in a closed position, and manually operable means for opening said door.

In testimony whereof I hereby affix my signature.

YONEZO TSUJINO.
